E. KARR

RANGE

Filed Jan. 9, 1928

INVENTOR:
EDWARD KARR.
BY *Arthur C. Lockett*
ATTORNEY.

UNITED STATES PATENT OFFICE.

EDWARD KARR, OF BELLEVILLE, ILLINOIS.

RANGE.

Application filed January 9, 1928. Serial No. 245,321.

The object of my device is to make a range for the burning of coal or wood or gas or combination coal and gas.

A further object is to devise a range of the character described provided with a radiating surface for heating the room in which the range is positioned. A still further object is to devise a range having a radiating surface at one end and having a circulation system which provides for efficiently heating said radiating surface with products of combustion that are usually lost in the conventional range. Among my objects is to provide a range having an efficient circulation system and to provide one that is made of few and simple parts that lend themselves readily to multiple production and that may be easily and cheaply made.

With these and other objects in view, my invention has relation to certain novel features of construction and arrangement of parts as will be hereinafter more fully described, illustrated in the drawing and pointed out in the claim.

Fig. 1 is a side elevation of a range made in accordance with my disclosure.

Fig. 2 is a front elevation of said range.

Fig. 3 is a transverse fragmental sectional elevation on the line 3—3 of Fig. 1 and Fig. 4 is a cross sectional elevation on the line 4—4 of Fig. 3 with the heating surface removed.

In the drawing a combination gas and coal range is shown. The circulation system for the gas portion of the range is not illustrated and may be of any conventional form. Numeral 5 designates the range generally having the ash box 6 and the fire box 7. A conventional grate not shown may be used. Numeral 8 designates the conventional side wall having the opening 9 formed therein near the top and centrally positioned. Numeral 10 designates a flue wall positioned on the left end of the range and secured thereto at the bottom by the offset 11 and to the upper surface of the range proper at 12. The securing means may be of the conventional type. The flue wall 10 flares upwardly from the central portion forming the sloping panel 13.

The path of the products of combustion is shown by the arrows indicated in all the figures. These products of combustion pass upwardly from the fire box 7 through the opening 9 into the flue formed between the side wall 8 and the flue wall 10 and thence downwardly to the bottom of said flue. On account of the sloping panel 13 the cross sectional area of the flue formed between the side wall 8 and the flue wall 10 is largest at the top and tapers downwardly to the central portion. This enables the products of combustion to expand in the largest area near the top, which expansion promotes the circulation of the products of combustion. The sloping panel 13 together with the remainder of the flue wall 10 form the radiating surface that functions to heat the room in which the range is positioned. Numeral 14 designates the conventional flue positioned centrally with respect to the coal portion of the range and in the rear of the range. Near the bottom of the rear wall of the range is formed the opening 15 connecting the flue between the side wall 8 and the flue wall 10 with the rear flue 16 which is in fluid communication with the flue 14. The products of combustion having arrived at the bottom of the flue between the side wall 8 and the flue wall 10 pass through the opening 15 into the rear flue 16 and thence into the flue 14 from which they are finally dispelled into the atmosphere.

What I claim and mean to secure by Letters Patent is:

In combination with a range having a flue formed between its side wall and an external side flue wall, the upper portion of said external flue wall protruding laterally and tapering downwardly from the top and means for circulating the products of combustion between the side wall and the external flue wall downwardly and then rearwardly to the flue of said range.

In testimony whereof I affix my signature.

EDWARD KARR.
